(57) **CLAIM**

The ornamental design for a user interface for a computer display, as shown and described.

DESCRIPTION

FIG. 1 is a front view of a user interface for a computer display showing the new design; and,

FIG. 2 is a front view of a second embodiment thereof. The broken line drawing of a computer display is for illustrative purposes and forms no part of the design.

1 Claim, 2 Drawing Sheets

FIG. 1

FIG. 2
